MARTIN LANDENBERGER, OF PHILADELPHIA, PENNSYLVANIA.

Design No. 4,233, dated July 19, 1870.

DESIGN FOR A SHAWL.

The Schedule referred to in these Letters Patent and making part of the same.

To all whom it may concern:

Be it known that I, MARTIN LANDENBERGER, of Philadelphia, in the county of Philadelphia and in the State of Pennsylvania, have invented certain new and useful Improvements in Design for Shawls or other wearing apparel; and do hereby declare that the following is a full, clear, and exact description thereof, reference being had to the accompanying drawing and to the letters of reference marked thereon making a part of this specification.

This design for shawls is represented in the accompanying drawing, and consists of the plain ground or stripe A, following which is a checkered stripe, B, next

to which is the plain stripe C, then the series of narrow stripes D, and then the spotted stripes E.

Any colors, or series of colors, may be used in this design.

What I claim is—

The design for shawls, as herein shown and described.

In testimony that I claim the foregoing, I have hereunto set my hand this 14th day of May, 1870.

MARTIN LANDENBERGER.
